Primary Examiner — Lauren D McVey*Assistant Examiner* — Justin A Johnson(74) *Attorney, Agent, or Firm* — Bayramoglu Law Offices LLC(57) **CLAIM**

The ornamental design for a plant light, as shown and described.

DESCRIPTION

FIG. 1 is a perspective view of a plant light showing my new design;

FIG. 2 is a front elevational view thereof;

FIG. 3 is a rear elevational view thereof;

FIG. 4 is a left side elevational view thereof; and

FIG. 5 is a right side elevational view thereof;

FIG. 6 is a top plan view thereof; and,

FIG. 7 is a bottom plan view thereof.

The broken lines shown in the drawings are for the purpose of illustrating the environmental structure and forms no part of the claimed design.
